UNITED STATES PATENT OFFICE

THOMAS M. HEERMANS, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE

CENTRIFUGAL PUMP

Application filed October 30, 1931. Serial No. 572,024.

This invention relates in general to the art of centrifugal pumps and relates more specifically to improvements in centrifugal pumps used for pumping liquids.

5 An object of the invention is to provide a more or less tangential discharge of a pump, as related above, with novel means for changing its capacity.

Another object of the invention is that the 10 means for changing the capacity of a centrifugal pump comprises a capacity changing Venturi design nozzle formed either to be readily insertible in the discharge outlet of the pump or so as to be readily externally attached to the discharge outlet.

Another object of the invention is to form the discharge outlet and provide the same with initially thick walls so that the desired capacity changing of the pump may be effected 20 while retaining its Venturi design by merely reaming or machining out the outlet by the required amount.

Another object of the invention is to provide a centrifugal pump having operating 25 characteristics which well adapt the pump for use in furnishing a substantially constant quantity of a liquid while operating at satisfactory efficiencies and against heads of different magnitudes.

30 It has been found that by providing the substantially tangential outlets of centrifugal pumps with a Venturi form or design of flow passage having its constricted portion immediately adjacent the cut-off of the pump that

35 certain eddies are eliminated and that the flow lines of the liquid still within the pump proper are changed or adjusted to permit of a more pronounced regainer action in the diffuser portion of the outlet. This invention

40 with its modified forms contemplates arrangements accomplishing the above noted desired results and additionally provides designs of outlets for centrifugal pumps and/or means cooperating with such outlets

45 for changing the capacity of the pumps without necessitating adjustments of the pump casing or the substitution of different runners. And by merely changing the area of the constriction of the Venturi form or design of flow passage and correspondingly changing

the flare of the regainer portion thereof a desired capacity change may be effected. If the area of the constriction of the Venturi design of flow passage is reduced below the normal area just beyond the cut-off or lip 55 section of the pump as originally constructed and designed it has been found that its efficiency at the reduced capacity may be slightly greater than the efficiency of a pump designed for operation at this value of reduced capacity. The Venturi form or design of discharge outlets according to this invention has the further advantage in that pumps provided therewith have operating characteristics which show that they may be operated over 60 appreciable ranges of head without an accompanying appreciable change in quantity of liquid pumped per unit of time over these ranges. This makes centrifugal pumps provided with the improvements constituting 70 this invention adapted to a field from which centrifugal pumps were heretofore considered to be excluded, namely, to the field of supplying constant quantities of liquid, regardless of slight changes in the pressure at 75 the outlet.

Other objects and advantages of the present invention will become apparent from a consideration of the detailed description hereinafter found in the specification and of the 80 drawing accompanying the same and on which like reference numerals refer to similar parts or elements in all of the several views.

Fig. 1 is an end elevational view of a centrifugal pump, the tangential discharge outlet thereof and the novel Venturi nozzle insertible in the outlet being shown in longitudinal cross-section.

Fig. 2 is a longitudinal cross-sectional view of a discharge outlet of a centrifugal pump with a slightly modified form of Venturi nozzle insertible in the outlet, the nozzle also being shown in longitudinal cross-section.

Fig. 3 is a longitudinal cross-sectional view of a slightly different discharge outlet of a centrifugal pump with another modified form of Venturi nozzle attachable to and located entirely externally of the discharge 100

outlet, the nozzle also being shown in longitudinal section.

Fig. 4 is a longitudinal sectional view of a discharge outlet having a Venturi form of flow passage cast integral with the nozzle portion, of a centrifugal pump of relatively large size and capacity.

Fig. 5 is a longitudinal sectional view of a discharge outlet having a Venturi form of flow passage cast integral with the nozzle portion, of a centrifugal pump of relatively small capacity.

Fig. 6 is a graph of operating curves of a centrifugal pump having a discharge outlet as shown in Fig. 1 and also a graph of operating curves of the same centrifugal pump with the outlet thereof provided with an insertible Venturi nozzle as shown in Figs. 1 and 2.

Referring to Fig. 1 the centrifugal pump casing 1, of usual construction, is provided with a shaft 2 alined with the suction inlet 3 of the pump. The shaft 2 carries a runner 4 having vanes 5 which act upon the liquid flowing into the casing through the inlet 3, when the runner 4 is rotated at high speeds, and force the liquid into the collector chamber 6 surrounding the runner 4. The collector chamber 6 terminates in a tangential discharge outlet 7 having a boss 8. The boss 8 is provided with interior threads 9 preferably tapered as shown for direct cooperation with complementary external threads 10 formed on an intermediate portion of a novel Venturi nozzle 11. The enlarged portion 12 of the nozzle 11 is provided with internal threads 13 also shown to be tapered, to facilitate the application of the conduit member 14 to the nozzle 11. The reduced portion 15 of the nozzle 11 is tapered to permit its being received within the tapered discharge outlet 7. The flow passage of the nozzle 11 is of a Venturi form having a constriction 16 located closely adjacent to the cut-off 17 of the pump casing, which cut-off is rounded as shown to prevent the formation of eddies and so as to desirably cooperate with the adjacent mouth portion formed by the curved annular inner surface terminating inwardly 50 of the constriction 16. Outwardly beyond the constriction 16 the flow passage of the nozzle 11 is provided by a diverging annular surface 18 which forms the regainer section of the nozzle. It is in this section of the nozzle 11 where the velocity head is substantially and efficiently converted into pressure head.

In Fig. 2 a slightly modified insertible Venturi nozzle 11 and discharge outlet 7 are shown. The intermediate portion of the nozzle 11 instead of the screw threads is provided with an external, apertured annular flange 19 and the outlet 7 is provided with an external, apertured annular flange 20 to which the nozzle 11 is secured by bolts 21

passing through the apertures in said flanges. Similarly the enlarged outer end of the nozzle 11 is provided with an external, apertured annular flange 22 registerable with an annular flange 23 on the conduit member 14 so that said member may be secured to the nozzle 11 by bolts 24 passing through the apertures in said flanges. The parts and their arrangement otherwise are the same as shown in Fig. 1.

In Fig. 3 a further modified form of discharge outlet is shown in which the cut-off 17 of the pump is located closely adjacent to an annular supporting surface 25 provided directly by a portion of the material of said cut-off and an external flange 26 terminating the discharge outlet 7. A Venturi nozzle 11 having an external, annular flange 27 terminating the same adjacent the constriction 16 thereof may therefore be advantageously employed in a centrifugal pump provided with a discharge outlet as shown in this figure. The nozzle 11 may be secured to the outlet 7 by any suitable means cooperating directly with the flanges 27 and 26. The opposite end of the nozzle 11 may likewise be provided with an external, annular flange 28 for direct cooperation with a like flange 23 on a conduit member 14 for the purpose of fixedly securing the member 14 to the nozzle 11.

Fig. 4 shows the discharge outlet 7 of a centrifugal pump wherein the desired Venturi form or design of flow passage is provided directly by the inner surface of the outlet. This surface provides a constriction 16 adjacent the rounded cut-off 17 of the pump, said constriction terminating at one side thereof in a regainer portion 18 as in the detachable nozzles of Figs. 1, 2 and 3. Similarly to the construction of Figs. 2 and 3 the discharge outlet 7 in this construction is provided with an external, annular flange 30 and the conduit member 14 with a like flange 23 whereby the member 14 may be secured to the discharge outlet 7 by means cooperating with the flanges 30 and 23. The thought underlying this construction is that the core box for forming the nozzle portion of a centrifugal pump not having a Venturi form of discharge outlet flow passage or having such an outlet, may be modified by making the discharge outlet forming pattern portion of the core box detachable from the collector forming pattern portion of the core box. In this way by merely substituting for the discharge outlet pattern portion of the given core box a discharge outlet core portion having the desired Venturi form a centrifugal pump having the same interior collector passage but having the desired Venturi form or flow passage in its discharge outlet may subsequently be readily cast. This construction scheme is, as stated before, especially suitable in the con-

struction of the larger sizes of centrifugal pumps.

Fig. 5 similarly to Fig. 4 shows the interior surface of the discharge outlet 7 of a centrifugal pump as directly providing a Venturi form of flow passage. It differs from the showing of Fig. 4 primarily in that the cut-off 17 of the pump is removed a greater distance from the constriction 16 of the Venturi form of flow passage, provided directly by the discharge outlet, so that the mouth 31 thereof leading into the constriction 16 is of a pronounced conical form. The discharge outlet 7 may be provided with an external flange 30 and the conduit member 14 with a cooperating flange 23 for the purpose described in connection with the similar showing of Fig. 4. A construction as shown in Fig. 5 is especially suitable for use in pumps of smaller capacities than those in which the construction shown in Fig. 4 is suitable. The walls of the discharge outlet 7 of this figure, it will be noted, are shown to be relatively thick so that the original capacity of the pump may be changed by reaming or machining out the material forming the regainer surface portion 18 so as to obtain the desired area of the constriction 16 in the reduced state of the discharge outlet.

Advantages from the standpoint of the manufacturer of centrifugal pumps:

Say a year's business in three sizes of small pumps is as follows: 125 pumps having $1\frac{1}{2}$ " diameter outlets; 100 pumps having 2" diameter outlets and 75 pumps having 3" diameter outlets, and that these pumps on stock orders of twenty-five cost \$125.00, \$130.00 and \$135.00 respectively, to build. Now if the same range of capacities can be covered by a single 3" pump with two Venturi nozzles giving respectively, the capacities of the smaller outlet diameter pumps mentioned, it means that three hundred pumps of one size can be manufactured, larger stock orders can be put through at one time, and more special tools can advantageously be provided to reduce the cost where only one size of pump is considered as against three pump sizes. The economies resulting from producing one size in larger stock orders obviously should bring the production cost of the three hundred 3" pumps below that of the three hundred pumps divided among the three sizes mentioned.

Advantages to the manufacturer and to the dealer:

The keeping of factory and dealers' stock is facilitated and the inventory reduced, since a dealer could stock one pump and two Venturi nozzles of the required sizes instead of three different pumps to take care of three distinct capacity requirements.

Advantages to the user:

The novel Venturi nozzle permits of very materially and appreciably extending the range of utility of a particular casing and

runner, since the 2" outlet diameter pump, for example, may have a rating of 200 G. P. M. at 75' head and 1750 R. P. M. This same runner in a different suitable casing would be good for 400 G. P. M. at 300' head by using a suitable motor to increase the speed of the runner to 3500 R. P. M. The different suitable casing would be required to take care efficiently of the increased output of the runner as by using the original casing designed for 200 G. P. M. the efficiency would be found not to be satisfactory and the output of the runner exceeding its rated output at the doubled speed would not be desirable. However, by using a capacity reducing Venturi nozzle, the capacity of the pump using the original casing and the same runner while operating the runner at the doubled speed could be maintained at approximately 200 G. P. M. its normal output rating and efficient performance realized. Here again it is seen that a single casing and runner can be made to take the place of two casings and with the single casing two ranges of performance realized of 75' head, at 200 G. P. M. capacity at 1750 R. P. M. and 300' head, at 200 G. P. M. capacity at 3500 R. P. M.

Further, for small capacity, high head pumps, it is usually necessary to make the runner in two pieces either riveted or welded together, if a small enough opening at the periphery is to be obtained to keep the capacity within the desired limits. About as narrow an outside or peripheral opening at the runner outlet that can be provided by casting the runner in one piece is an opening $3/16$ " x $7/32$ " wide. A runner for 75 G. P. M. 300' head pump should be about $7/64$ " wide at the outside.) The wider one piece runner has several advantages over the narrow runner comprising two pieces fastened together in that it has a lower manufacturing cost, is better mechanically and is less subject to stoppage of its passages by small foreign particles contained in the liquid being pumped. The wider runner can be used in a pump provided with the disclosed novel capacity controlling Venturi nozzles as this nozzle enables the capacity of a pump having a wider runner than a runner which could be used in the standard design of pump, to be efficiently controlled. In other words, the novel capacity changing nozzle herein disclosed is advantageously employable to secure a comparatively small capacity from a pump which would not be practical to cast to small enough dimensions for best efficiency when using a normal design.

That the novel Venturi nozzle herein disclosed is both a capacity and a head changing device can be seen from the performance curves shown in Fig. 6. The dot-dash curves shown in this figure are plotted from test data of a standard centrifugal pump having the straight line-element discharge-outlet

flow-passage substantially as shown in Fig. 1 and having a 2" diameter inlet and outlet and 3500 R. P. M. normal speed rating for its runner. While the solid line curves shown in this figure are plotted from test data of this same pump operating at its rated speed 3500 R. P. M. but with a 2" x 1 1/2" Venturi nozzle inserted as shown in Fig. 1 in the discharge outlet of the pump. The capacity values in G. P. M. are plotted as abscissæ and the corresponding head values, efficiency values and brake horsepower values, as ordinates. The curves designated E, H and B are respectively, the efficiency, head and brake horsepower curves for the standard pump and the corresponding solid line curves for the same pump when provided with the stated size of novel Venturi nozzle have been designated *e*, *h* and *b* respectively. These curves reveal the following information: That the maximum efficiency of the stated pump when provided with the stated size of Venturi nozzle and operated at the rated speed 3500 R. P. M. is reduced from about 71% at 100 G. P. M. capacity to 59% at 60 G. P. M. capacity and the head value at 60 G. P. M. capacity is reduced slightly from about 114' to 106' but it may here be stated that a similar type of pump except for the size which would ordinarily be used for 60 G. P. M. and designed for best efficiency at this 60 G. P. M. capacity rating gives 102' head with 58% efficiency. The said larger size pump for which the solid line curves were drawn and having the stated novel nozzle at 60 G. P. M. capacity, therefore has a 1% higher efficiency at this capacity rating than a pump which would ordinarily be used for this capacity rating of 60 G. P. M. The brake horsepower curve to the break-off point for the stated standard pump when operated with the stated nozzle and at the same speed 3500 R. P. M. is seen to coincide with the brake horsepower curve for the stated standard pump when operated at this speed. Between 60 G. P. M., the capacity at which the stated standard pump provided with the stated Venturi nozzle has its maximum efficiency when operated at 3500 R. P. M., and about 85 G. P. M. capacity, the curves *e*, *h* and *b* are seen to have knees, the portions of these curves below the knees thereof coincide in vertical line portions of their lengths. This characteristic of the curves, as clearly shown, for the standard pump operating with the stated novel Venturi nozzle in the discharge outlet has the following significance.

The knee of the head curve H for the stated standard pump is seen to terminate at about 20' of head and at about 165 G. P. M. capacity at which point the runner is handling all of the water this runner is capable of passing and this is not a desirable or satisfactory operating condition. The knee of the curve *h* for the stated standard pump using the

stated Venturi nozzle is, however, seen to terminate at about 70' head and at about 85 G. P. M. capacity, which is well within the limits the runner will handle satisfactorily so there should be no disadvantage in operating this latter pump at a break-off capacity of 85 G. P. M. if desired. The adaptability of a centrifugal pump having the disclosed Venturi nozzle in fields where high efficiencies are relatively unimportant as compared with the desirability of maintaining a substantially constant output of pumped liquid in G. P. M., therefore, becomes apparent. This may be done by pumps designed for some average pressure of the pressure range below the knees of the head curve and zero pressure head with the Venturi nozzles herein disclosed fixing or determining the delivery capacities of the pumps.

Having now fully described the various modifications of the novel Venturi design of discharge outlet for centrifugal pumps and set forth the principle of operation of the invention as measured by these modifications and stated their advantages and applicabilities, it is to be further understood that the invention is not to be limited to the exact details of construction and of operation herein shown and described, for various modifications within the scope of the claims may occur to persons skilled in the art to which the invention appertains.

It is claimed and desired to secure by Letters Patent:

1. In a centrifugal pump, a substantially tangential discharge outlet, said outlet being provided with a Venturi design of flow surface changeable to vary the capacity of the pump.

2. In a centrifugal pump, a substantially tangential discharge outlet, said outlet having associated therewith a Venturi design of flow surface changeable to vary the capacity of the pump.

3. In a centrifugal pump, a substantially tangential discharge outlet, and a capacity changing hollow member attachable to said outlet.

4. In a centrifugal pump, a substantially tangential discharge outlet, and a hollow member having a Venturi design of flow surface, said member being attachable to said outlet and being provided for the purpose of changing the capacity of the pump.

5. In a centrifugal pump, a substantially tangential discharge outlet having an inner surface constituted by substantially straight line elements, and a capacity changing hollow member attachable to said outlet.

6. In a centrifugal pump, a substantially tangential discharge outlet having an inner surface constituted by substantially straight line elements, and a hollow member having a Venturi design of flow surface, said member being attachable to said outlet and being pro-

- vided for the purpose of changing the capacity of the pump.
7. In a centrifugal pump, a discharge outlet having an inner surface constituted by substantially straight line elements, and a hollow member having a Venturi design of flow surface, said member being attachable to said outlet and being provided for the purpose of changing the capacity of the pump.
- 10 8. In a centrifugal pump, a substantially tangential discharge outlet, and a capacity changing hollow member insertible in said outlet.
9. In a centrifugal pump, a substantially tangential discharge outlet, and a hollow member insertible in said outlet, said member being provided with a Venturi design of flow surface and being insertible for the purpose of changing the capacity of the pump.
- 20 10. In a centrifugal pump, a discharge outlet, and a nozzle having a Venturi design of flow surface, said nozzle being insertible in said outlet for the purpose of changing the capacity of the pump.
- 25 11. In a centrifugal pump, a substantially tangential discharge outlet, a cut-off forming a portion of said outlet, said outlet being provided with a Venturi design of changeable flow surface, the constriction forming portion of said surface being located adjacent said cut-off, said changeable surface being provided for the purpose of changing the capacity of the pump.
- 30 12. In a centrifugal pump, a substantially tangential discharge outlet, a cut-off forming a portion of said outlet, said outlet being provided with a Venturi design of changeable flow surface, said surface and said cut-off being formed and related to prevent the formation of eddies adjacent the cut-off, said changeable surface being provided for the purpose of changing the capacity of the pump.
- 35 13. In a centrifugal pump, a substantially tangential discharge outlet, said outlet having a Venturi design of flow surface and being comprised of relatively thick walls, the capacity of the pump, while maintaining a Venturi design of flow passage, being changeable by operating directly upon the material constituting the walls of said outlet.
- 40 14. In a liquid pumping system, a centrifugal pump, the discharge outlet of said pump being provided with changeable means having a Venturi design of flow surface having a constriction area less than the fixed normal area of the outlet of the pump, said means being provided for the purpose of changing the capacity of the pump.
- 45 15. A centrifugal pump comprising a casing, a substantially tangential discharge outlet for said casing, an inlet to said casing, a runner rotatable within said casing, a conduit member adapted to be connected to said discharge outlet, the flow passage between the
- inner surface of said discharge outlet and said member being changeable and being defined by two truncated cone surfaces joined in their smallest diameters by a short throat surface, whereby the capacity of the pump is changeable and the pump is adapted to supply a constant quantity of liquid at any changed capacity notwithstanding appreciable changes in head against which the pump then operates.
